UNITED STATES PATENT OFFICE

131,279

DESIGN FOR AN INDUSTRIAL TRUCK

Elverton W. Weaver and John Gordon Rideout,
Cleveland Heights, Ohio, assignors, by mesne
assignments, to Towmotor Co., Cleveland,
Ohio, a copartnership

Application August 15, 1941, Serial No. 102,848

Term of patent 7 years

To all whom it may concern:

Be it known that we, Elverton W. Weaver and John Gordon Rideout, citizens of the United States, residing at Cleveland Heights, in the county of Cuyahoga and State of Ohio, have invented a new, original, and ornamental Design for Industrial Trucks, of which the following is a specification, reference being had to the accompanying drawings forming part thereof and

wherein Fig. 1 is a side perspective view of an industrial truck showing our new design; Fig. 2 is a rear perspective view, and Fig. 3 is a front perspective view thereof.

We claim:

The ornamental design for an industrial truck, as shown.

ELVERTON W. WEAVER.
JOHN GORDON RIDEOUT.
